(57) **CLAIM**

The ornamental design for a performance capture marker housing, as shown and described.

DESCRIPTION

FIG. 1 is an exploded top view of a performance capture marker housing that features a first piece and a second piece; FIG. 2 is a front view of the first piece in FIG. 1, shown separately for clarity of illustration; FIG. 3 is a bottom view of the first piece in FIG. 2; FIG. 4 is a front view of the first piece in FIG. 2; FIG. 5 is a side view of the first piece in FIG. 2; FIG. 6 is a top view of the second piece in FIG. 1, shown separately for clarity of illustration; FIG. 7 is a bottom view of the second piece in FIG. 6; FIG. 8 is a front view of the second piece in FIG. 6, the rear view of the second piece being a mirror image thereof; FIG. 9 is a side view of the second piece in FIG. 6, the other side view of the second piece being a mirror image thereof; FIG. 10 is a top perspective view of the performance capture marker housing in FIG. 1, shown in an engaged and unlocked configuration; FIG. 11 is a top perspective view of the performance capture marker housing in FIG. 1, shown in an engaged and locked configuration; FIG. 12 is a cross sectional view taken along the line A-A, in the direction of the arrows, of the top perspective view in FIG. 11; FIG. 13 is a bottom perspective view of the performance capture marker housing in FIG. 11; FIG. 14 is a top view of the performance capture marker housing in FIG. 11; FIG. 15 is a bottom view of the performance capture marker housing in FIG. 11; FIG. 16 is a front view of the performance capture marker housing in FIG. 11, the rear view being a mirror image thereof; and, FIG. 17 is a side view of the performance capture marker housing in FIG. 11, the other side view being a mirror image thereof.

The broken lines (dash) illustrating portions of the performance capture marker housing, form no part of the claimed design.
